Primary Examiner — Darcey E Gottschalk(74) *Attorney, Agent, or Firm* — Seed IP Law Group LLP(57) **CLAIM**

The ornamental design for a shoulder therapy device, as shown and described.

DESCRIPTION

FIG. 1 is an isometric view of a shoulder therapy device showing my new design from one perspective.

FIG. 2 is an isometric view thereof from another perspective.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof; and,

FIG. 8 is a right side elevational view thereof.

Stippling and tangency lines shown in the drawings are intended to represent the three-dimensional contours of the design, and are not intended to indicate surface decoration. In the drawings, the broken lines show portions of a shoulder therapy device that form no part of the claimed design.
